UNITED STATES PATENT OFFICE.

JACKSON W. BRUTON, OF GUTHRIE, MISSOURI.

GARMENT ATTACHMENT.

1,078,826.

Specification of Letters Patent. Patented Nov. 18, 1913.

Application filed March 12, 1912. Serial No. 683,309.

To all whom it may concern:

Be it known that I, JACKSON W. BRUTON, citizen of the United States, residing at Guthrie, in the county of Callaway and 5 State of Missouri, have invented certain new and useful Improvements in Garment Attachments of which the following is a specification.

This invention relates to attachments for 10 the pockets of garments to hold pencils, fountain pens and like implements, and prevent them from falling from the pocket, and has for one of its objects to provide a simply constructed device which may be readily 15 attached to and removed from the garment, and which does not injure the garment or require any permanent fastening devices.

Another object of the invention is to provide 20 a device of this character which may be readily applied and in which provision is made for guiding the attaching devices.

With these and other objects in view, the 25 invention consists in certain novel features of construction as hereafter shown and described, and then specifically pointed out in the claims, and in the drawings illustrative of the preferred embodiment of the invention: Figure 1 is a view of a garment from the outside, with the outer member of the 30 improved device in position thereon; Fig. 2 is a view of a portion of a garment from the inside, with the inner member of the improved device in position thereon; Fig. 3 is a detached perspective view of the fastener 35 portion of the improved device; Fig. 4 is a cross section on the line 4—4 of Fig. 1; Fig. 5 is a perspective view of the inner clamp member; Fig. 6 is a perspective view of the outer clamp member. Fig. 7 is a perspective view of the improved device illustrating 40 a modification in the construction.

Corresponding and like parts are referred to in the following description and indicated in all the views of the drawings by the 45 same reference characters.

The improved device comprises in general two plates preferably of metal, one to be located externally of the garment and the other to be located internally of the garment 50 opposite the outer plate and with yieldable fastening devices employed to connect the two plates in position. The outer plate is represented as a whole at 10 and with the upper edge turned over as shown at 11, to 55 form a wire-holding socket and with perforations 12 near the ends. The plate 10

is also formed with tongues 21 to fold over the resilient members and assist in holding the same, as hereafter explained. The inner plate is represented as a whole at 13, 60 and is provided with apertures 14 near the ends and with notches 15 in the lower edge spaced apart the same distance as the apertures 12 and 14. The plate 13 is also provided with a lip 16 to receive the terminals 65 of the holding pins, as hereafter explained. The yieldable fastening device is formed preferably from a single piece of wire and comprises a longitudinal body portion 17 bent into coils 18 at the terminal of the 70 body portion and with the remaining portions of the wire extended through the coils as shown at 19, and thence extended laterally as shown at 20, the terminals of the portions 20 being pointed to enable them to 75 be forced through the garment. The plates 10—13 will be of sufficient length to extend partly across a pocket near the opening as represented in Fig. 1, in which a portion of a garment is represented at 24 with the 80 pocket flap at 22.

The wire portion of the device is first attached to the plate 10 by inserting the lateral portions 20 through the apertures 12 and forcing the body portions 17 beneath 85 the folded-over lip 11, and then compressing the lip upon the wire. This disposes the springs 18 against the outer face of the plate 10 at the ends with the pins 20 projecting beyond the plate. To attach the device, 90 the plate 13 is first located upon the outer face of the flap 22 where the device is to be located and the notches 15 utilized as guides to determine the points where the pins are to be thrust through the garment. 95 The plate 13 is then removed and the plate 10 disposed upon the flap 22. The plate 13 is then located on the inner face of the garment with the protruding portions of the pins extending through the apertures 100 14. The pins 20 are then turned up and engaged with the lip 16 which thus locks the two plates and the fastening device to the garment. It will be understood that the portions 19 of the fastening device will 105 be sufficiently short so that when the device is attached the springs will be compressed and thus apply the necessary tension to hold the device in position and prevent accidental displacement while at the same time the 110 springs will yieldably support the plates to permit pencils, fountain pens, or other arti-

cles to be readily inserted into and removed from the pocket by applying sufficient force, but which will engage the articles with sufficient strain to prevent them from falling 5 from the pocket or becoming otherwise accidentally displaced.

The improved device is simple in construction, can be inexpensively manufactured and applied, and which will not detract from the appearance of the garment to 10 which it is applied.

The plates may be of any length to correspond to pockets of varying lengths and may be of any suitable metal and plated, 15 galvanized, or otherwise treated or protected. The plates may be colored to correspond to the garment to which they are attached so that their appearance will not be observable.

20 In Fig. 7 is shown a modification of the construction consisting in forming the member 17 in two portions as represented at 23-23 engaging in opposite ends of the rolled over portion 11, but this would not 25 constitute a departure from the principle of the invention or sacrifice any of its advantages.

Having thus described the invention, what is claimed as new is:

30 1. An attachment for garments comprising an outer plate having a longitudinally extending holding socket and adapted to bear externally of a garment, an inner plate adapted to bear against the inner side of a 35 garment, a fastening device including a U-shaped wire body at its intermediate portion engaging said socket and with the end portions extending through the plates, and means for detachably securing the end portions 40 of the inner plate.

2. An attachment for garments comprising coacting plates adapted to bear against the outer and inner sides of a garment, fastening devices extending through said 45 plates, means for yieldably engaging said

fastening devices with one of said plates, and means for detachably connecting the fastening devices to the other plate.

3. An attachment for garments comprising coacting plates adapted to bear against the outer and inner sides of a garment, guide members extending from one of said plates and through the other plate and guiding the same, and a spring connected to each of said guide members and bearing 55 against the adjacent plate.

4. An attachment for garments comprising coacting plates adapted to bear against the outer and inner sides of a garment, fastening devices each including a coil 60 spring bearing upon one of the plates and with one terminal of the coil extending through the plates, and means for detachably connecting said extending terminals to the other of said plates. 65

5. An attachment for garments comprising coacting plates adapted to bear against the outer and inner sides of a garment, guide members extending from one of the plates and slidably through the other plate, 70 a coil spring connected by its outer helix to each of said guide members and bearing by its inner helix against the adjacent plates.

6. An attachment for garments comprising coacting plates adapted to bear respectively upon the outer and inner sides of a garment, resilient members connected to one of said plates, fastening devices extending from said resilient members and projecting 80 through the other plate, and means for detachably engaging said fastening devices with said last-mentioned plate. 75

In testimony whereof I affix my signature in presence of two witnesses.

JACKSON W. BRUTON. [L.S.]
